Jul. 7, 2006 (JP) 2006-018066

CLAIM

(51) **LOC (8) Cl. 28-03**

The ornamental design for a hair treatment accelerating
device, as shown and described.

(52) **U.S. Cl. D28/10; D28/17**

DESCRIPTION

(58) **Field of Classification Search** D28/10,
D28/11, 12, 15, 16, 17, 20; 132/212; 392/380-381;
34/99

FIG. 1 is a plan view of the hair treatment accelerating
device of the present invention;

See application file for complete search history.

FIG. 2 is a front view thereof;

(56) **References Cited**

FIG. 3 is a bottom view thereof;
